UNITED STATES PATENT OFFICE.

ELMYR A. LAUGHLIN, OF OREGON, ILLINOIS.

DRAFT BIGGING.

Application filed May 16, 1924. Serial No. 713,787.

To all whom it may concern:

Be it known that I, ELMYR A. LAUGHLIN, a citizen of the United States, residing at Oregon, in the county of Ogle, State of Illinois, have invented certain new and useful Improvements in Draft Riggings; and I do hereby declare the following to be a full, clear, and exact description of the invention, such as will enable others skilled in the art 10 to which it appertains to make and use the same.

This invention relates to new and useful improvements in draft gear, and particularly to draft gear for use in connection 15 with railway cars.

One object of the invention is to provide a draft gear which is double acting and frictional, and wherein the initial stress is easy, and which will gradually increase until the 20 maximum is reached, thereby obviating the usual shocks incident to coupling and uncoupling.

Another object is to provide a draft gear of this character wherein the opposite ends 25 of the mechanism work against a central element, and not against each other.

Other objects and advantages will be apparent from the following description when taken in connection with the accompanying 30 drawing.

In the drawing:

Figure 1 is a perspective view of a draft gear, the upper wider face being toward the observer.

Figure 2 is a longitudinal sectional view 35 on the line 2—2 of Figure 1.

Referring particularly to the accompanying drawing, 10 and 11 represent a pair of housings which have their mutually adjacent ends open, said housings being adapted to be supported by the usual sills of a car, and between the stops thereof, said housings being embraced by the usual draw yoke. As the sills, and draw yoke are of ordinary 40 construction, illustration is thought unnecessary. The inner faces of the sides of the closed end of each of the housings 10 and 11 are formed with the beveled faces 16, to which reference will be made later herein.

Disposed within one end of the housing 10 are the blocks 18 and 19, having the parallel side faces 20 and 21, respectively, and the rear flat faces 22 and 23, respectively, which bear against the inner face of 45 the end wall of the housing. The other ends of the blocks 18 and 19 have the forwardly

converging faces 24 and 24', the latter being slightly shorter than the former, whereby the angle therebetween lies at one side of the longitudinal center of the block. Similarly shaped blocks 25 and 26 within the housing 10 have the longer oblique faces 27 bearing against the shorter oblique faces 24', of the blocks 18 and 19, while the shorter oblique faces 28, of the blocks 25 and 26 bear against the oblique faces 16 of the same. 50 Against the flat transverse face 29, of each block 25 and 26, there is disposed a spring end retaining member 30. Disposed longitudinally and centrally 55 in the housing 10, is an elongated member 31, the opposite ends of which have the converging oblique faces 32 and 33, respectively, the former bearing against the longer oblique faces 24, of the blocks 18 and 19, 60 the angle between the faces 32 being somewhat more acute than the angle between the faces 33.

Disposed within the other end of the housing 11 are the blocks 34 and 35, which 65 are of the same shape as the blocks 18 and 19, except that the outer transverse end faces 36, are oblique, and bear against the wear plates 37, which are disposed against the correspondingly inclined faces 37 of the 70 end wall of this housing. Similar blocks 38 and 39 are engaged with the sides of the housing 11 and with the adjacent oblique faces 33, of the central member 31, as well as the shorter oblique faces of the blocks 34 75 and 35. Spring end retaining members 40, similar to the members 30, are disposed against the transverse faces of the blocks 38 and 39. Disposed between the members 30 and 40 are the coil springs 41. 80

Normally the parts are in the position shown in Figure 2, and when the housing 11 is moved longitudinally in a direction to exert a pulling or draft stress, the housing will be drawn so that its beveled faces 16 will bear against the shorter oblique faces 24' of the blocks 38 and 39, while at the same time the longer oblique faces of said blocks 34 and 35 are engaged by the shorter oblique faces of the blocks 34 and 35. The faces 37 of the 85 housing will frictionally bear against the faces 36 of the blocks 34 and 35. The blocks 34 and 35 move against the adjacent end faces 33, of the member 31, so that their longer oblique faces slide on the oblique faces 33. This causes the blocks 34 and 35 to move transversely of the housing 11, 90

well as longitudinally thereof, and by reason of their engagement with the blocks 38 and 39, these latter blocks will be forced outwardly in the direction of the sides of the housing, as well as in a direction longitudinally thereof, said blocks 38 and 39 pushing the retaining members 40 against the adjacent ends of the springs 41. These springs resist the movement of the members 40 with the result that the member 31 will be forced longitudinally of the housing by the blocks 34 and 35. It will be noted that this central member 31 has its ends projecting into the open ends of the housings 10 and 11. It will also be noted that the member 31 has the pins 31' extending from its opposite wider faces, adjacent the ends thereof, and that these pins extend through slots 10' and 11', respectively, of the housings 10 and 11. These pins are for the purpose of maintaining the housings in proper relation to each other, as a guide for the plunger 21, and to prevent separation of the parts, while the gear is in shipping transit, or while placing the gear in a car. After the gear is properly disposed in the car, the pins may be removed, or permitted to break or snap off, by engagement of the end walls of the slots 10' and 11' during the operation of the gear.

As the member 31 moves longitudinally, the oblique faces 32, at the other end thereof, cause the blocks 18 and 19 to be moved transversely of the housing 10, and these blocks, in turn, cause the blocks 25 and 26 to exert pressure against the members 30, which results in a compressing force against the adjacent ends of the springs 41. The combined frictional engagement between the blocks, the blocks and the member 31, and between certain of the blocks and the housings, together with the tendency of the springs to resist compression, serve to cause a gradually increasing tension in the draft gear, with the result that by the time that the projections 30' and 40', of the spring retainers 30 and 40, have moved into abutting engagement, all danger of shock or jar will have been prevented, and the car moved forwardly with an easy action.

When the draft yoke is moved in the other direction so as to exert a pushing or buffing action against the housing 10, the blocks 18, 19, 25, and 26 push the member 30 to produce a compression of the springs 41. The member 31 will also be moved longitudinally, and through the cooperative engagement of this member and the blocks 34, 35, 38, and 39, the members 40 will be moved to exert a compressing action against the adjacent ends of the springs. Thus when either of the housings is moved, by the action of the draft yoke thereagainst, the cooperation of the various beveled blocks results in a compressing action against the

springs from both ends. The initial movement of either of the housings produces a comparatively rapid and easy movement of the blocks at the end at which the force is applied, but as the force increases the friction between the oblique faces of the various parts increases, due to the resisting action of the springs, the action on the car will be easy and without jar or shock. This is especially desirable when coupling or uncoupling.

While I have shown a single spring on each side of the member 31, it should be understood that two large springs may be used on each side thereof, or a single large spring may encircle the member 31, and engage with the retaining members 30 and 40.

What is claimed is:

1. A draft rigging including housings, springs extending between and into the housings, a central longitudinally movable member, and wedge members of different degrees of acuteness cooperating with each other and cooperating with the central member for moving said member and compressing the springs.

2. A draft rigging including housings, a longitudinally slideable and centrally disposed member having its opposite ends within the housings said ends being provided with faces converging at different degrees of acuteness, springs extending between and within the housings, retaining means for the ends of the springs, and wedge members within the housings and cooperating with each other and with the ends of the central member for urging the retaining means into compressing engagement with the opposite ends of the springs.

3. A draft rigging including housings, a central longitudinally movable member extending between and into the housings, said member having faces converging at its opposite ends at different angles of acuteness, the housings having oblique faces, blocks disposed within the housings and bearing thereagainst and having converging faces, springs between the housings, retaining members at the opposite ends of the springs, said blocks frictionally engaging the opposite ends of the central member, and blocks slidably engaging the oblique faces of the housings, certain of the converging faces of the first blocks, and bearing against the spring retaining members.

4. A draft gear including a plunger having wedge-shaped ends of different degrees of acuteness, followers at the ends of the plunger, friction blocks between the ends of the plunger and the followers, said blocks having wedge-shaped ends of different degrees of acuteness corresponding to and cooperating with the corresponding ends of the plunger and means for urging the friction blocks into engagement with the plunger.

5. A draft gear including a central plunger having its ends wedge-shaped and of different degrees of acuteness, followers at the ends of the plunger, friction wedge blocks in the followers engaging with the ends of the plunger, springs on each side of the plunger, spring retaining means at the ends of the springs, and friction wedge blocks slidably bearing against the first wedge blocks and with the spring retaining means, the ends of the plunger and the blocks engaging therewith having their wedge ends formed at different degrees of acuteness. 20
6. A draft gear including a central plunger having wedge-shaped ends, followers at the ends of the plunger, friction wedge blocks in the followers and engaging therewith, the wedge-shaped ends of the plunger being formed at different degrees of acuteness, said 25
- ends bearing against faces of corresponding angles of said friction wedge blocks, and springs between certain of the friction wedge blocks at one end of the plunger and certain of the friction wedge blocks at the other end of the plunger. 30
7. A draft gear including a central plunger, followers at opposite ends of the plunger, friction blocks between the plunger and the followers and operatively engaged therewith, the ends of the plunger having outwardly converging faces, the said faces at one end of the plunger converging at an angle more acute than at the other end of the plunger, and resilient means coacting with the friction blocks, and being subject to compression thereby. 35

In testimony whereof, I affix my signature.
ELMYR A. LAUGHLIN.
